LOCK FOR LAUNDRY WASHING MACHINES

Carl Schwarz, Rosedale, N. Y.

Application November 2, 1937, Serial No. 172,351

4 Claims. (CL 220—32)

The present invention is directed to an improvement in laundry machines, and more specifically relates to rotary cylindrical washing machines.

5 In this type of machine, sometimes known as a wash wheel, wherein the machine is in the form of a rotary, hollow barrel of considerable size, to wash by rotation, a considerable quantity of clothes, a longitudinal portion of the cylinder is so constructed as to form a door to permit access to the interior of the wash cylinder or drum. This predicates the provision of a hinge between one side of the door, and latch or locking means on the edges of the door, opposite to 10 the hinged portion, whereby the door may be unlocked, then raised, and after the desired operations of removal or placement of goods, the door is closed and locked in closed position.

During the rotary washing operation, the door 20 is submitted to a series of intermittent shocks due to intermittent pounding of the wet and heavy material therein as it is rotated. This action, if the door locks are not well fitted causes the door to eventually work loose and permits 25 of the bulging of the section between the hinges, as illustrated in Fig. 7.

The present invention constitutes an improvement in the door locking means including additional auxiliary locking means in connection with 30 the so-called loading-shelf, whereby the same is utilized in its operatively hinged connection with barrel portion of the washer, to reinforce the door lock, to absorb the intermittent operative shocks thereon and to prevent buckling of the 35 adjacent staves of the barrel and door.

The foregoing and other features of advantage will be apprehended as the herein description proceeds and it will be obvious that modifications may be made in the structure herein disclosed, 40 without departing from the spirit hereof, or the scope of the appended claims.

In the drawing,

Fig. 1 is a fragmentary front view of the barrel;

45 Fig. 2 is an enlarged, fragmentary sectional view taken on line 2—2, Fig. 1, looking in the direction of the arrows;

Fig. 3 is an enlarged, fragmentary front view, sectioned in parts, of the dual lock and its adjacent barrel and door connections;

Fig. 4 is a sectional view taken on line 4—4, Fig. 3, looking in the direction of the arrows;

Fig. 5 is a sectional view, taken on line 5—5, Fig. 3, looking in the direction of the arrows;

55 Fig. 6 is a fragmentary view in section, similar

in part to Fig. 2, showing the loading shelf in gap bridging position;

Fig. 7 is a longitudinal sectional view taken at the longitudinal center of one of the door staves showing the objectionable bulging action of the 5 staves of the door section, which is obviated by the present improvement; and

Fig. 8 is a reduced, longitudinal sectional view taken at about the region of the locks, to illustrate the cooperative stiffening action of the 10 locks on the door and the stiffening action of the hinge extensions on the door stave ends.

As shown in the drawing the washing drum, generally denoted by B, is rotatably supported by bearings X—X in an outer fixed cylinder, generally denoted by D, and which cylinder is provided with a permanent access opening O, Figs. 1 and 2, so that the drum B may be exposed to manual manipulation therethrough.

The cylinder D may be permanently supported 20 on a support not shown, and the drum B rotated by any suitable and customary drive means not shown, but well understood in the art.

The drum B is constructed preferably of wooden staves S, spaced slightly apart, at their edges, 25 so as to allow the wash water to enter from the cylinder D, which contains water therein, the level of which is below the lower edge of the access opening O. The staves are suitably and fixedly mounted at their ends to opposing circular 30 heads H—H, Figs. 1, 3 and 8 in the customary manner.

The drum B is provided with an opening therein, which is closed by a door C, which is pivotally hinged at Y, Figs. 1 and 2, so that it may be 35 lifted upwardly as shown dotted in Fig. 2, to permit of the inserting, or removing of laundry therein or therefrom.

The door section is constructed of spaced staves S, similar to those of the drums B, and their opposite ends are suitably affixed to opposed curved stave end reinforcing extensions M and M of the coacting hinge members N—N between and in which the pivots Y—Y are mounted. The hinges M—N are preferably made of metal.

As seen in Fig. 2, the upper hinge members N are preferably mounted upon a thickened sill piece stave T, which frames and reinforces the upper edge of the opening O. The lower edge of opening O is also framed and reinforced by a 50 thickened sill piece stave T. Thus, sill pieces T and T' reinforce the upper and lower edges of the opening in drum B against the forces reacting upon the door C, when it is locked in the drum B.

The stave S' is provided with openings such 55

as R, through which the lugs P project, as in Fig. 5, into the casing face I.

The curved door C, as will be seen in Figs. 1, 5 and 8, fits in between the heads H—H, when closed and the curved contour thereof is therefore in cylindrical contour with the drum B, Fig. 2.

The exposed, outer edge of upper sill T', Fig. 2 is rabbeted as at f, along its length, with one step, and the exposed outer edge of lower sill T is rabbeted at g and h, Figs. 2 and 4, forming two steps along the length of the outer edge thereof.

The rabbet f acts as a jamb for the upper edge 15 of door C when closed. The rabbets g and h are provided to permit of the fitting therein of a stepped and pivoted loading shelf E—e, Fig. 4, which is, normally, when the door C is closed, set upright in the seat formed by the rabbet g, and 20 forms a support or backing E along the entire length of the lower back face of door C, thereby acting as a rigidifying stop E for the door, the stave S' of which may be provided with a rabbet i, Fig. 4, in which E is seated.

25 The loading shelf E—e, as seen in Fig. 4, is shaped, in cross section, like a right angle, one shorter leg e of which is provided with a bored butt 19, which is pivotally supported upon a pintle 23, which in turn, is firmly held in and 30 between the spaced and bored butt extension 20—20 of the hinge support bracket 21. The hinge support bracket 21 is, in turn firmly attached by screws 22 to the outer face of sill 35 stave T, as shown in Fig. 3.

35 It is to be understood that there are two of the hinged connections as above described, one at, or adjacent each of the ends of the door C, as shown in Figs. 5 and 8.

The elongate loading shelf, as above described, 40 is thus pivoted, to be located as an interiorly disposed back brace or jamb for the door C when it is closed, and when it is swung down as in Fig. 6, after the door is opened, to form a bridge over the gap between the outer surface of the 45 drum B and the inner surface of the shell D, thereby to cover said gap and thus prevent laundry from falling into said gap during removal or replacement of a load.

The rabbeted step h receives therein the angled flange k of the bracket 21, Fig. 4, to support the bracket in operative position.

The back plate E of the loading shelf is provided with two outstanding lugs P, on its front face as viewed in Fig. 8, and as shown in Figs. 55 3, 4 and 5. These lugs are each located near the opposed ends of the loading shelf, but spaced therefrom. Each lug is provided with an aperture 16, preferably square in cross section, near their outer ends, best seen in Fig. 4, into and out 60 of which a square sectioned auxiliary bolt L' is movably engaged and disengaged. The bolt L' is reciprocally carried in a latch housing, generally denoted by l, Figs. 3, 4 and 5, which is mounted 65 on the lower door stave S', and moves therewith, said stave being recessed as at j, Fig. 5, to seat the housing, which is held therein by screws 7, Fig. 3, set in the surrounding flanges thereof and the stave S'.

70 The housing includes a hollow casing 2, shown partially in section, in Fig. 3, and in other sections, Figs. 4 and 5. The bolt L', Figs. 3 and 5, when engaged with the bore of lug P, is slidably held in the offset arm 14 by a boss V at the offset 75 end thereof. On the bolt L', at the rear of the

boss V is located a fixed collar 17, against which one end of a coiled spring 18 rests, the coiled spring surrounding the bolt L', with its opposite end resting in a recessed spring seat 4, Fig. 3.

The offset arm 14 is integral with a slide bar 5 13, from which it is offset, and which is mounted for reciprocation in a bearing 6 in the rear wall of a spring enclosing chamber 5, Fig. 3. The outer end of slide bar 13 is exposed beyond the casing and is threaded to receive thereon the 10 threaded boss 11 of a manually manipulable handle F, and a lock nut 12 locks said handle in the proper operative plane and position on the slide bar 13.

A coiled spring 15 is mounted on slide bar 13, 15 the ends of said spring contacting between the nut 12 and the rear wall bearing 6.

As thus described both springs 18 and 15 tend at all times to stress the slide bar 13 and the bolt L', towards the left, as viewed in Figs. 3 and 20 5, and thus maintain the door C in locked position on stave S'.

The main lock, generally denoted by L, Fig. 3, comprises a flat bolt 8, which is integral with the handle F, and which is reciprocally mounted 25 in a bearing boss m which is an integral part of the elongate hinge section M, near the bottom end thereof, Fig. 3. The outer end of the bolt is chamfered, at its striker end as at 9, so that when the door C is closed with a slam, the bolt 30 8 automatically operates to throw back and to engage itself and the slide bolt L' into their respective coacting locking means.

The outer end of the bolt 9 extends beyond its guide bearing m, which latter coacts with bearing 6 to align slide bar 13 and its appurtenant coacting parts, and the extending end 9, Figs. 3 and 5 engages with a mortise 10, which is located in the adjacent face of the cylinder head H, Fig. 5, so that when the bolt 8 is in operative position, it engages its end 9 into said head mortise 10 and thereby each lock locks the cover C to the heads H—H, at its opposite sides firmly, with no tendency to become loosened accidentally.

From the foregoing description it will be seen, that by the provision of dual side cover locks with the coacting lugs on the pivoted loader shelf, and the coaction of the hinge structures, a firmly locked and easily operated door closure is provided, eliminating the tendency to stave bulge as illustrated in Fig. 7, where the stave S', or staves S of the cover C are distorted by the impact of the laundry W thereagainst.

In operating the machine to load or unload the wash drum B, after cessation of the movement of drum B, the cylinder is manually rotated until the door C is registered with the opening O in D, and the two latches F—F operated to disengage their locking means and the door is then swung upwardly to dotted position shown in Fig. 2, and the loading shelf E is dropped to gap bridging position shown in Fig. 6. Both hands of the operator may be used, one on each locking mechanism, to simultaneously operate both left hand and right hand lock mechanisms.

The elongate butts, M—M, of the hinges, as will be seen in Fig. 1, extend from the hinge points Y to the bottom of stave of door C and engage the opposite ends of the staves S and S' by means of bolts or screws 8.

From the foregoing it will be noted that the loading shelf E and door C of the drum B are so arranged that the door locks the shelf within the 75

inner face of the door, thus keeping the outer surface of the drum B substantially flush, and interlocking the shelf and door when the drum is closed for rotation.

5 Having thus described the invention, what is claimed is:

1. In combustion, a horizontal drum having a longitudinal loading opening extending from head to head of the drum; a loading shelf hinged at the lower edge of the opening to cover the lower margin of the opening; a door hinged at its upper edge to the drum covering said opening and disposed against the front face of the shelf and provided with lower openings and guide bearings near the heads; the shelf being provided with lugs projecting through said lower openings respectively and each provided at its end with an aperture; each head having a mortise with which said bearings may register; housings secured to the door each receiving one of said apertured ends and provided with a bolt bar guide; a main bolt slideable in said bearing and guide and spring pressed into said mortise and provided with a lateral off-set having a boss; an auxiliary bolt slideable in said boss; a spring for pressing the bolt into the aperture; and means on the auxiliary bolt and engageable by the boss for withdrawing the auxiliary bolt from the lug whenever the main bolt is withdrawn.

2. In combination, a horizontal drum having a loading opening extending from head to head; a loading shelf member of L-shaped cross-section adapted to rest in the lower edge of the opening with its upper part extending upward to cover the lower margin of the opening and its base extended outwardly and hinged to the outer face of the drum; and a door hinged at the upper part to the drum and covering said opening and disposed against the shelf base and the front face of the shelf when closed.

3. In combination, a horizontal elongated drum having a longitudinal loading opening therein bounded at opposite sides by upper and lower longitudinal sills, the sills and opening extending from head to head; adjacent faces of the sills being rabbeted to form outwardly facing shoulders; a sheet metal loading shelf of L-shaped cross section adapted to rest in the lower rabbet with its base extended outward and its upper part extending upward to cover the lower margin of the opening; said base being provided, remote from the heads with outwardly downwardly extended hinge members; means hinging said members to the outer face of the lower stave; a door hinged to said upper sill and adapted when closed to be disposed against the upper shoulder, the shelf base, and against the front face of the shelf; and means for locking said shelf, door and heads together.

4. In a washing machine comprising a rotary drum, having an access opening therein, and having heads at opposite ends thereof, the combination therewith of a hinged door for closing said opening, an upper and a lower sill piece stave framing the upper and lower edges of said opening, said door being hinged from said upper sill piece, an elongate loading shelf pivotally mounted upon the lower sill piece and having outwardly projecting apertured lugs thereon, an angular leg on said shelf forming a support for said lugs, said leg being parallel with the plane of the door forming a stiffener for the rear face of the stave forming the free edge of said door, said stave being provided with apertures in register with said lugs whereby said lugs may protrude therethrough when the door is closed and bolts carried by the door and engaged in the apertures of the lugs.

CARL SCHWARZ. 40
